(57) **CLAIM**

The ornamental design for an exhibition stand, as shown and described.

DESCRIPTION

FIG. 1 is a perspective view of an exhibition stand showing my new design;

FIG. 2 is a front view thereof;

FIG. 3 is a left side view thereof;

FIG. 4 is a right side view thereof;

FIG. 5 is a top view thereof;

FIG. 6 is an exploded perspective view thereof;

FIG. 7 is an exploded front view thereof;

FIG. 8 is an exploded left side view thereof; and,

FIG. 9 is an exploded right side view thereof.

The bottom and rear views are flat and include no surface ornamentation.

The broken lines in the figures show portions of the exhibition stand and environment that form no part of the claimed design.
